NELS A. LUNDBERG, OF MOLINE, ILLINOIS.

HOLDING AND DISPLAY RACK FOR LITERATURE, MUSIC, AND ART.

1,366,813.

Specification of Letters Patent. Patented Jan. 25, 1921.

Application filed March 6, 1920. Serial No. 363,780.

To all whom it may concern:

Be it known that I, NELS A. LUNDBERG, a citizen of the United States, residing at Moline, in the county of Rock Island and

5 State of Illinois, a carpenter, have invented new and useful Holding and Display Racks for Literature, Music, and Art, of which the following is a specification.

My invention relates to holding and display racks having oscillating display leaves which fold, which display leaves by means of springs attached thereto, are calculated to hold displays of literature, music and art on either side, and folded may be swung to 15 the wall, or opened into the room, and the objects of my invention are to provide a means of displaying literature, art and music for inspection or sale in large quantities without injury in handling, or any part 20 hiding the other, and of putting the same away, protecting it from dust, dirt and flies, without handling, and of utilizing space.

I attain these objects by the mechanism illustrated in the accompanying drawings in 25 which:

Figure 1 is a plan view of the display rack closed, with its leaves perpendicularly extended.

Fig. 2 is a plan view of the display rack 30 closed, with its leaves swung parallel to the wall.

Fig. 3 is a side elevation of the display rack, with its leaves perpendicularly extended in working position.

35 Fig. 4 is an enlarged fragmentary vertical section through the leaf.

Fig. 5 is an enlarged fragmentary horizontal section through the leaf.

Fig. 6 is a side elevation of the top of the 40 post.

Fig. 7 is a side elevation of the bottom of the post.

Fig. 8 is a side sectional view of the top bracket and pivot.

45 Fig. 9 is a side sectional view of the bottom bracket and pivot.

Fig. 10 is a plan view of the oscillating angle support.

Fig. 11 is a side elevation of a bottom 50 spring.

Fig. 12 is a side elevation of a top spring.

Similar numerals refer to similar parts throughout the several views.

My invention is expected to be connect- 55 edly attached perpendicularly to a perma-

nent structure 15, or to a slat not shown attached to the wall, by ordinary angle brace means 14 and pivot spike bolt 6 at the top end of oscillating post 1.

The apex of the angle attachment 14 at 60 the top is provided with boxing means 14^a for insertion of a journaled pivot spike bolt 6, provided in the top end of oscillating upright post 1, which may be made of wood or iron, and constitutes the axle of my machine, for the purpose, in connection with other pivot means 7, provided at its bottom end, of holding it in perpendicular position and supporting the leaves and braces attached thereto.

70 Pivot bolt 6 is an ordinary spike bolt driven into a hole, not shown, in the top end of oscillating post 1, and is held in place by a plate washer 5 and a ferrule 4, and is held within journal 14^a by nut means 6^a.

75 The bottom of oscillating post 1, being likewise provided with pivot spike bolt 7, plate 5 and ferrule 4, excepting the pivot spike bolt 7 at bottom is not provided with a nut but is fitted in a plate 16^a secured to 80 the floor 16 or to a slat not shown, securely attached upon the floor, so that when the oscillating post 1 is attached in position it will oscillate upon its pivots.

Conveniently near to and upon the ends 85 of oscillating post 1, I provide screw nut clip means 3, for the purpose of binding a pair of angle supports 2 to the said oscillating post 1, as shown in Figs. 3, 6 and 7.

Angle supports 2 are two in number, each 90 composed of ordinary angle iron and each having their respective ends bent forming obtuse angles in conformity to each other, as shown in Fig. 10, each presenting a horizontal surface and a perpendicular side. 95 The horizontal surfaces are provided with a plurality of holes 2^a, the perpendicular sides also provided with two holes 2^b, which latter holes are for the introduction of the ends of screw nut clip means 3, in securing 100 the said angle braces 2 upon the top and bottom ends of oscillating post 1, and angle supports 2 are for the purpose of mounting between said angle supports 2 of a plurality of display leaves 8.

105 In securing the angle supports 2 upon the oscillating post 1, the middle part of the angle support 2 is placed with its perpendicular flange against the face of the post 1 and held in place by means of clip 3, which 110

fits securely around oscillating post 1, said angle support 2 thus presenting a flat fitting surface to said oscillating post 1 between the holes 2^b, of said angle support 2, its ends 5 being bent at acute angles from the face toward the back of said oscillating post 1, for the purpose of giving a wider spread to display leaves 8, when mounted thereon.

The horizontal surface of the angle support 2 is provided with multiple holes 2^a 10 for the insertion of the pivots 11^a and 12^a of leaf supports 11 and 12, as shown in Fig. 3, when the same are attached to the respective top and bottom ends of oscillating display leaves 8 mounted between angle supports 2.

Leaf supports 11 and 12 are respectively provided at one end with pivots, the pivot of one thereof, for sake of safety, being 20 provided with a screw thread and nut 11^c to secure the same in hole 2^a of angle support 2, the other being plain, said leaf supports 11 and 12 being provided with multiple holes 11^b and 12^b in their surface for 25 securing them by ordinary bolt or screw means, not shown, to oscillating display leaves 8, as shown in Fig. 3.

Oscillating display leaf 8 is composed of a thin center surface 8^b set edgewise composed of any firm light substance preferably beaver board and has its edges securely bound by and rabbeted into a band frame strip 8^c of any desired material in such manner as to form a right-angular band 35 frame around the center surface 8^b, displaying its right-angular projection on one or both sides of such center surface 8^b as desired, for the purpose of holding the center surface 8^b in rigid position, and of furnishing 40 means for securing the oscillating display leaf 8 upon and between the leaf supports 11 and 12, and of providing means for the better securing upon said center surface, 8^b of divisional strips 8^a as shown in 45 Fig. 3.

Each oscillating display leaf 8, as desired is provided upon either side of its thin center surface 8^b, with one or more divisional strips 8^a of any desired style preferably of a 50 width corresponding to the protruding width of the flanged edge of band frame strip 8^c and of a length corresponding to the perpendicular width of center surface 8^b, and arranged perpendicularly across said center surface 8^b 55 and right-angularly disposed thereto, and spaced from each other perpendicularly upon said center surface 8^b, as desired. Said divisional strips 8^a are placed upon said center surface 8^b for the purpose of rendering the 60 same more rigid, and for the further purpose of dividing the center surface 8^b into sections as desired, corresponding to the wishes of the owner with reference to the matter desired to have displayed, and being secured 65 to band frame 8^c by screw means not shown

and to said center surface 8^b by brad or screw means not shown, their spacing may be changed as desired.

Between divisional strips 8^a and between band frame 8^c and divisional strips 8^a as 70 shown in Figs. 3, 4 and 5 are provided upon center surface 8^b multiple spring holding devices 9 and 10; spring 9, being a special bottom spring, as shown in Fig. 11; springs 10 are arranged in pairs above springs 9, 75 and above each other. Springs 9 are secured to band 8^c at their bottom ends by mortise and screw means not shown. Springs 10 are secured to center surface 8^b, 80 at their lower ends by rivet means 10^e inserted in holes 10^f and all are made of light narrow, thin strips of spring metal, their tops bending outward at 10^b to admit the insertion of display matter without tearing the same, spring 10 having an outwardly disposed offset 10^a in the middle and an outwardly disposed right-angular offset 10^c, 85 below the same in such manner as to cause the top 10^b to lie firmly against the offset 10^a of such center surface 8^b, when the bottom 90 ends 10^d of said spring holding device 10 is securely attached to said center surface 8^b as previously shown. Bottom spring 9 has a right-angular bent end 9^a provided with a flanged extremity 9^c and provided with 95 screw holes 9^e and has its top bending outwardly at 9^b, for the purpose of freely admitting the display matter. In operation the tops of springs 9 and the tops of springs 10 excepting the upper row, rest upon the 100 offset 10^a of the oppositely arranged springs, all for the purpose of adding tension in holding literature, music and art, close and securely in display upon such display leaf 8, 105 in any desired position, which arrangement is disclosed in Figs. 3, 4, and 5.

It will be observed that the display leaves 8, when so arranged and mounted may extend compactly out into a room as shown in Fig. 1, or may be compactly swung with 110 their side to the wall as shown in Fig. 2, or may be swung out opened like a book as shown in Fig. 3, and as many as may be desired may be mounted, and their contents disclosed, or protected from the dust by 115 folding the device.

I claim:

1. In a holding and display rack, a perpendicularly disposed oscillative post, pivotally supported between a plate washer at 120 its lower end and a journal at its top end, the oscillative post supporting securely by clip means at its respective ends angulate leaf braces and a plurality of oscillative display leaves, pivotally disposed between said angulate leaf braces, for the purposes specified. 125

2. In a holding and display rack, having an oscillative post supporting between angulate leaf braces a plurality of oscillating display leaves, an oscillating display leaf hav- 130

ing at opposite corners of one of its sides, securely attached display leaf braces each brace having oppositely disposed pivot ends engagingly operating in corresponding holes 5 provided in the horizontal surfaces of angular braces respectively supported upon the oscillative post; a band frame securely attached to its edges; one or more perpendicular divisional slats right-angularly disposed, 10 regularly arranged securely attached to its center surface and to said band frame; a plurality of springs arranged in pairs securely attached upon the center surface of said display leaf between perpendicular divisional slats and perpendicular band frames, for the purposes specified.

3. A holding and display rack consisting of an oscillative post supported at its upper end by a wall bracket, at its lower end by a 20 flat plate washer; a pair of angulate leaf braces secured thereto by clip means; a multiplicity of oscillative display leaves relatively mounted upon said angulate leaf supports, by pivot means provided on the corresponding corners of one of their edges; frame means for binding the edges of said display leaves; means for dividing the center surface of the display leaves into sections; spring means for securing literature, 25 music and art products upon such center surface within such sections; the leaves capable of being opened and closed like a book and oscillated from side to side by means of said oscillative angulate leaf support and pivots, for the purposes specified.

4. In a holding and display rack having oscillative display leaves; a display leaf having a center surface perpendicularly divided into spaces, each of the spaces having 30 a pair of bottom spring means secured thereon and plural pairs of other spring means disposed thereon arranged at regular intervals in alinement above said bottom springs, the leaves mounted upon brackets secured 35 upon an oscillative post, for the purposes specified.

5. In a holding and display rack having oscillative display leaves provided with spring means for holding advertising matter thereon; including a bottom spring having

its top end outwardly curved, an outwardly disposed right-angular offset near its bottom end, and a plurality of holes provided in its bottom end for its attachment by other means to said display leaf; a top spring having 55 its top end outwardly curved, an outwardly disposed offset arranged midway of its perpendicular length, another right-angular offset outwardly disposed near its bottom end, and a plurality of holes provided in 60 its bottom end for its attachment by other means to said display leaf, for the purposes specified.

6. In a holding and display rack, an oscillative post perpendicularly disposed, 65 provided at either end with a journaled pivot spike bolt, inserted securely therein; the spike bolt at the top end provided beyond the journaled portion at its extremity with screw threads and a nut; said post also 70 provided at either end engaging said spike bolts with a plate washer; said post also provided at either end with a ferrule band adjacent to said plate washer, securely attached to said post; said post also provided 75 with flanged offsets outwardly disposed at either end, supporting at either of said ends between said flanged portion and said ends, band clip means having screw thread ends and a corresponding screw nut; said post 80 also provided at either end between the respective flanged portions and the pivots and securely attached by band clip means connectedly attached by nut means, with plural angle supports, having each a horizontal and a perpendicular side, the middle of the perpendicular side fitted flush to said post secured thereto through holes provided therein by band clip means, the ends of said angle supports acutely angulated, said 85 angles rearwardly disposed facing each other; and in such manner as to oscillate with and actuate as a part of said oscillating post, all for the purpose of engagingly supporting upon said post, of a plurality of display leaves, substantially as shown.

NELS A. LUNDBERG.
